CLAIM

The ornamental design for an injection tube, as shown and described.

DESCRIPTION

FIG. 1 is an isometric view of an injection tube according to a first embodiment;

FIG. 2 is an elevation view from the left side thereof;

FIG. 3 is a top plan view thereof;

FIG. 4 is a bottom plan view thereof;

FIG. 5 is an elevation view from the right side thereof;

FIG. 6 is an elevation view from the front side thereof; and FIG. 7 is an elevation view from the rear side thereof.

FIG. 8 is an isometric view of an injection tube according to a second embodiment;

FIG. 9 is an elevation view from the left side thereof;

FIG. 10 is a top plan view thereof;

FIG. 11 is a bottom plan view thereof;

FIG. 12 is an elevation view from the right side thereof;

FIG. 13 is an elevation view from the front side thereof; and FIG. 14 is an elevation view from the rear side thereof.

The broken lines depict portions of the injection tube that form no part of the claimed design.
